UNITED STATES PATENT OFFICE.

THOMAS JOSEPH NOLAN, OF ALBANY, NEW YORK.

PUZZLE.

SPECIFICATION forming part of Letters Patent No. 656,039, dated August 14, 1900.

Application filed September 6, 1899. Renewed June 13, 1900. Serial No. 20,184. (No model.)

To all whom it may concern:

Be it known that I, THOMAS JOSEPH NOLAN, a citizen of the United States, residing at Albany, in the county of Albany and State 5 of New York, have invented certain new and useful Improvements in Puzzles, of which the following is a specification.

My invention relates to puzzles, the object being to provide an inexpensive puzzle which 10 will be sufficiently difficult of solution to render it amusing and entertaining.

The construction of the improvement will be fully described hereinafter in connection with the accompanying drawings, which form 15 a part of this specification, and its novel features defined in the appended claim.

In the drawings, Figure 1 is a top plan view of a puzzle embodying the invention, and Fig. 2 is a section on the line 2-2 of Fig. 1. 20 The reference-numeral 1 designates a box or board of circular form provided at four equidistant points on its periphery with approximately-circular projections or extensions 2. A continuous vertical rim or wall 3 surrounds the board and its extensions 2. Each of the extensions is hollowed out to form 25 a pocket 4, and the center of the upper surface of the board is formed with a depression 5, constituting a central pocket. Each of the 30 pockets 4 communicates with the central pocket 5 by means of sinuous grooves constituting trackways and designated, respectively, by the numerals 6, 7, 8, and 9. Each of these trackways consists of a plurality of 35 convolutions, the innermost one of which terminates at the central pocket 5, the inner ends 10, 11, 12, and 13 of the trackways being disposed at equidistant points around the central pocket or in pairs, the members of each 40 pair being at diametrically-opposite points from each other with relation to the central pocket 5.

Each of the side pockets 4 is painted a different color—as, for instance, red, blue,

green, and white—and four balls or marbles 45 14, corresponding in colors to the pockets, are employed with the puzzle. A glass cover 15 is secured over the trackways, said cover resting upon the upper edge of the rim 3, and centrally upon the upper surface of this glass 50 cover is pasted or otherwise secured an opaque supplemental cover 16 to conceal the central pocket 5. This supplemental cover preferably contains advertising matter of any desired character. 55

The balls 14 are placed one within each of the side pockets with respect to their colors, the red ball in the red pocket, &c. The aim of the player is to cause all of the balls to pass from their respective pockets to the central pocket and then back to the pockets from which they started. To accomplish this, it will be apparent that each ball will have to return through the same track by which it traveled to the central pocket, and inasmuch 60 as all of the balls enter the center pocket and the latter is covered, so that the balls are concealed from the view of the player, it will require repeated manipulation to return the balls to their starting-pockets. 70

I claim—

A puzzle comprising a box or board formed with equidistant side pockets, and a central pocket; a series of independent trackways consisting of a plurality of convolutions, each 75 of said trackways connecting one of the side pockets with the central pocket corresponding in color to that of the pocket; a ball or marble for each side pocket; a transparent cover for the box or board and a supplemental opaque cover for the central pocket secured at the center of the transparent cover. 80

In testimony whereof I affix my signature in presence of two witnesses.

THOMAS JOSEPH NOLAN.
